UNITED STATES PATENT OFFICE.

ELMER ENNIS, OF ARAPAHO, OKLAHOMA.

LOADING APPARATUS.

1,278,891.

Specification of Letters Patent. Patented Sept. 17, 1918.

Application filed May 25 1918. Serial No. 236,606.

To all whom it may concern:

Be it known that I, ELMER ENNIS, a citizen of the United States, residing at Arapaho, in the county of Custer and State of Oklahoma, have invented certain new and useful Improvements in Loading Apparatus, of which the following is a specification, reference being had to the accompanying drawings.

10 This invention relates to certain improvements in loading apparatus and has relation more particularly to a device of this general character including a hoisting receptacle and primarily it is an object of the invention to provide an apparatus of this general character especially designed and adapted for use for loading a vehicle with ensilage stored within a pit silo.

It is also an object of the invention to provide a novel and improved apparatus of this general character including a mast supported for turning movement together with a hoisting receptacle coacting with said mast and wherein the mast is provided with means 25 for holding the receptacle in an elevated position after the same has been raised a predetermined distance.

Another object of the invention is to provide a novel and improved apparatus of this general character including a mast and a hoisting receptacle coacting with the mast together with means for maintaining the receptacle elevated and wherein said means comprises a mechanism whereby the receptacle may be readily released when it is desired to lower the same.

Furthermore, it is an object of the invention to provide an apparatus of this general character including a hoisting receptacle 40 having novel and improved means whereby the contents of said receptacle may be readily dumped therefrom under the influence of the weight of the load.

The invention consists in the details of construction and in the combination and arrangement of the several parts of my improved loading apparatus whereby certain important advantages are attained and the device rendered simpler, less expensive and 50 otherwise more convenient and advantageous for use, as will be hereinafter more fully set forth.

The novel features of my invention will hereinafter be definitely claimed.

55 In order that my invention may be the better understood, I will now proceed to de-

scribe the same with reference to the accompanying drawings, wherein:

Figure 1 is a view in elevation of a hoisting apparatus constructed in accordance 60 with an embodiment of my invention;

Fig. 2 is an enlarged fragmentary view partly in elevation and partly in section illustrating the holding mechanism as herein embodied for maintaining the receptacle elevated; 65

Fig. 3 is a vertical sectional view with parts in elevation of the structure illustrated in Fig. 2;

Fig. 4 is a horizontal sectional view with 70 parts in elevation of the structure as shown in Figs. 2 and 3;

Fig. 5 is a fragmentary view in elevation illustrating the arm or lever for throwing the holding mechanism into release position; 75

Fig. 6 is a view in bottom plan of the hoisting receptacle as herein embodied;

Fig. 7 is a fragmentary view partly in side elevation and partly in section illustrating the locking means for the swinging bottom panels as comprised in the receptacle structure; and 80

Fig. 8 is a fragmentary view in elevation of the cam and the operating lever therefor 85 as included in the locking mechanism carried by the receptacle.

As disclosed in the accompanying drawings M denotes a mast of predetermined dimensions and which has its lower end rotatably engaged with the bearing 1. The upper end of the mast M is provided with an upstanding trunnion 2 which is loosely directed through the central portion of the plate 3. Coacting with the plate 3 are the guy 95 lines 4 whereby the mast M is effectively maintained in a vertical position yet capable of rotation.

Extending outwardly from the mast and preferably at right angles thereto is a boom 100 B and which boom is immovable relative to the mast M. The outer end portion of the boom B and the upper end portion of the mast M are connected by the brace member 5 whereby an effective support is afforded 105 for the outer end portion of the boom B.

The outer end portion of the boom B is provided therethrough with the vertically disposed opening 6 in which is rotatably mounted the pulley 7 over which is directed 110 the flexible member F. One end of the member F is anchored to the bracket 8 de-

pending from the boom B at a point inwardly of the opening 6 and the opposite end portion of the member is adapted to be hitched to a draft team or a suitable pulling 5 or winding mechanism. The member F after leaving the pulley 7 is disposed over a pulley 9 rotatably supported by the upper portion of the mast M and then under the pulley 10 engaged with the lower portion of 10 the mast.

The member F intermediate the pulley 7 and the bracket 8 is disposed under the pulley 11 rotatably supported within the frame or body 12. In swivel connection 15 with the lower end of the frame or body 12 is an eye member 14 and interlocking with the eye member 14 is a hanger H including the oppositely arranged and upwardly facing hook members 15. Engaged with the 20 hook members 15 are the central portions of the yokes 16 and the extremities of the yokes 16 are engaged with the upstanding ears or brackets 17 carried by the corner portions of the receptacle R. It will be self-evident that when strain is imposed upon the member F the receptacle R will be elevated or hoisted, and vice versa.

Straddling the outer end portion of the boom B and suitably spaced longitudinally 30 thereof are the supporting members S in the form of an inverted U with the intermediate portions thereof resting upon the top of the boom and secured thereto by the bolts 18 or equivalent fastening means. The side 35 arms 19 of the members S depend below the boom B and terminate in the bearings 20 in which are fixedly secured the rods 21 arranged in parallelism and extending longitudinally of the boom B.

40 Pivotedly engaged at their lower portions with the rods 21 are the transversely alined upstanding locking members or plates 22 and the upper end portions of said members or plates 22 are constantly urged inwardly 45 through the medium of the expandible members 23 interposed between the upper portions of said members or plates 22 and the horizontally disposed and outstanding brackets 24 secured at their extremities to

50 the depending arms 19 of the members S. The bolts 25 or the like which secure the brackets 24 to the depending arms 19 each coacts with a pair of transversely alined arms 19 and affords means for connection 55 with the burs or stops 26 engaged thereon, and contacting with the inner faces of the arms 19 to maintain the arms 19 or more particularly the depending portion thereof against relative movement. Extending out-

60 wardly from the upper end of the member or frame 12 is the elongated shank 27 terminating in the enlargement or head 28. The outer or upper face of the head 28 is conical in form as indicated at 29 so that 65 as the frame or member 12 is elevated or

hoisted through the medium of the flexible member F the head or enlargement 28 will readily pass between the locking members or plates 22 so that the upper edges of said members or plates may engage beneath the 70 head or enlargement 28 for maintaining the frame or member 12 and the elements carried thereby in an elevated or hoisted position.

Secured to the under face of the boom B directly above the plates 22 is a housing or 75 boxing 30 having its lower face open and of a width slightly in excess of the radical diameter of the enlargement or head 28. The housing or boxing 30 receives the head or enlargement 28 and serves to protect the 80 boom B against injury by contact of said head or enlargement therewith and also serves to facilitate the locking engagement of the members or plates 22 with the enlargement or head 28 as said head or enlargement 85 28 is held by the housing or boxing 30 against undue lateral movement when the members or plates 22 are in operative engagement therewith.

Secured to the outer face of each of the 90 members or plates 22 is an outstanding arm 31 terminating in an upwardly directed extension 32 and which extension is normally substantially vertically disposed. Rotatably supported by each pair of horizontally alined arms 19 of the members S is a shaft 33 provided with an upstanding crank 34 adapted to contact upon outward swinging movement with the upper end portion of an adjacent extension 32 of an arm 31. 100 The forward end portion of one of the arms 33 is provided with the depending extension 35 with which is operatively engaged a rigid link 36 also operatively connected with an inwardly and upwardly directed extension 105 37 arranged at the outer end portion of the second shaft 33. By this arrangement both of the shafts 33 will be caused to rotate in unison but in reverse direction so that such unitary movement will result in freeing the 110 members or plates 22 from the head or enlargement 28 of the shank 27 when it is desired to lower the frame or member 12 and the elements supported thereby.

In order to impart the necessary outward 115 rocking movement to the cranks 34 one of the shafts 33 is provided with the inwardly directed extension 38 which has its outer end portion rotatably supported by the bearing 39 engaged with the mast M. 120 The extension 38 is provided with the upstanding arm 40 through the outer or free end of which is secured a flexible member F'. The member F' is of a length to be readily grasped by an operator so that when 125 it is desired to release the frame or member 12 it is only necessary to pull upon the member F'. Interposed between the arm 40 and the mast M is a retractile member 41 which serves to return automatically the 130

cranks 34 inwardly when the member F' is relieved of strain.

In order to limit the extent of outward swinging movement of the cranks 34 I provide the mast M with the outstanding stop member 42 with which the arm 40 is adapted to contact when swung or pulled downwardly through the medium of the flexible member F'.

10 The receptacle R may be constructed in any desired manner and be of any preferred capacity but as herein disclosed the bottom of the receptacle comprises two swinging sections 43 hingedly connected at their 15 outer longitudinal margins with the rod 44 supported by the depending bearings 45 carried by the sides of the receptacle R. When the sections 43 are at the limit of their swinging movement toward the receptacle R the bottom of such receptacle is 20 substantially closed.

The opposite ends of each of the sections 43 adjacent the free longitudinal margin thereof is provided with the outwardly directed extensions 46 and coated with each of said extensions 46 is a holding dog or latch 47 pivotally engaged with the end wall of the receptacle R. Each end of the receptacle R is provided with a pair of holding dogs or latches 47 and rotatably supported by the end of the receptacle R and between said latches or dogs 47 below their pivots 48 is a cam member 49. Upon rotation of the cam member 49 in one direction it will be at once understood that the latches or dogs 47 will be caused to move in unison but in reverse directions so that the latches or dogs will be disengaged from the extensions 46 so that the sections 43 may 35 drop so that the load carried by the receptacle R may be readily dumped or discharged therefrom.

Each of the cams 49 is provided with an upstanding lever 50. Operatively engaged 45 with the upper end portion of each of the levers 50 is a pitman 51 which is also operatively engaged with a rock arm 52 carried by an end portion of the shaft 53 supported by a side of the receptacle R and extending 50 in a direction longitudinally of each of the bottom sections 43.

The rock arms 52 are reversely directed as particularly illustrated in Fig. 1 and one of the levers 50 is extended and affords an 55 operating handle 54 and this lever is disposed through the guide 55 so that the lever is held against lateral movement when strain is imposed upon the handle 54 to release the dogs or latches 47 from the extensions 46. The lower portion of this lever 50 has secured thereto a retractile member 56 which is also suitably anchored to the adjacent end or wall of the receptacle R. The member 56 serves to normally 60 maintain the levers 50 in a vertical position

and the cams in a position whereby no obstruction is offered to the engagement of the latches or dogs 47 with the extensions 46.

Each pair of latches or holding dogs 47 above their pivots 48 are connected by an 70 expansible member 57 which serves to constantly urge the lower or working ends of the latches or dogs 47 inwardly so that the desired engagement of the latches or dogs 47 with the extensions 46 is assured. 75

My present invention is particularly adapted for use in the removing or ensilage from a pit silo and in practice the mast is initially swung or rotated to position the boom above the silo so that the receptacle R can be lowered therein. After the receptacle R has been loaded, strain or pull is imposed upon the member F through the medium of a draft animal or other means and which results in the elevation of the receptacle R until the member or frame F or more particularly the shank 27 thereof is engaged with the members or plates 22. The mast M is then swung to position the boom B above the vehicle whereupon pull is 85 imposed upon the arm 40 to release the members or plates 22 from the shank 27 whereupon the receptacle R is lowered. After the receptacle R has been properly positioned desired pull is imposed upon the handle 54 which results in the release of the sections 43 whereupon the contents of the receptacle R will be readily dumped or discharged into the receptacle. 95

From the foregoing description, it is 100 thought to be obvious that a loading apparatus constructed in accordance with my invention is particularly well adapted for use by reason of the convenience and facility with which it may be assembled and 105 operated and it will also be obvious that my invention is susceptible of some change and modification without departing from the principles and spirit thereof and for this reason I do not wish to be understood as 110 limiting myself to the precise arrangement and formation of the several parts herein shown in carrying out my invention in practice except as hereinafter claimed. 115

I claim:

1. A loading apparatus comprising an elevated support, a hoisting member provided with an upstanding headed shank, means for moving the hoisting member relative to the support, swinging members carried by the support, means for constantly urging said members in one direction to engage the same beneath the head of the shank for holding the hoisting member elevated, an outstanding arm carried by each 120 of the members, and cranks carried by the support and engageable with the arms upon movement of the cranks in one direction for disengaging the members from the head. 125

2. A loading apparatus comprising an 130

- 15 elevated support, a hoisting member provided with an upstanding headed shank, means for moving the hoisting member relative to the support, swinging members carried by the support, means for constantly urging said members in one direction to engage the same beneath the head of the shank for holding the hoisting member elevated, an outstanding arm carried by each of the members, and cranks carried by the support and engageable with the arms upon movement of the cranks in one direction for disengaging the members from the head, said cranks being movable in unison but in reverse directions.
- 20 3. A loading apparatus comprising an elevated support, a hoisting member provided with an upstanding headed shank, means for moving the hoisting member relative to the support, swinging members carried by the support, means for constantly urging said members in one direction to engage the same beneath the head of the shank for holding the hoisting member elevated, an outstanding arm carried by each of the members, cranks carried by the support and engageable with the arms upon movement of the cranks in one direction for disengaging the members from the head, and means 25 for normally maintaining the cranks in inoperative position.
- 25 4. A loading apparatus comprising an elevated support, a hoisting member provided with an upstanding headed shank, means for moving the hoisting member relative to the support, swinging members car-

ried by the support, means for constantly urging said members in one direction to engage the same beneath the head of the shank for holding the hoisting member elevated, an outstanding arm carried by each of the members and provided with upstanding extensions, and rock members carried by the support inwardly of the upstanding extensions of the arms and engageable with said extensions for moving the members out of engagement with the head of the shank.

5. A loading apparatus comprising an elevated support, a hoisting member provided with an upstanding headed shank, means for moving the hoisting member relative to the support, swinging members carried by the support, means for constantly urging said members in one direction to engage the same beneath the head of the shank for holding the hoisting member elevated, an outstanding arm carried by each of the members and provided with upstanding extensions, rock members carried by the support inwardly of the upstanding extensions of the arms and engageable with said extensions for moving the members out of engagement with the head of the shank, and means connecting the rock members to cause the same to move in unison but in reverse directions.

In testimony whereof I hereunto affix my signature in the presence of two witnesses.

ELMER ENNIS.

Witnesses:

M. O. DAWSON,
A. M. MCKEE.
